C. L. NEDOMA,

VEHICLE.

APPLICATION FILED JULY 13, 1916.

1,213,893.

Patented Jan. 30, 1917.

UNITED STATES PATENT OFFICE.

CHARLES L. NEDOMA, OF DETROIT, MICHIGAN.

VEHICLE.

1,213,893.

Specification of Letters Patent. Patented Jan. 30, 1917.

Application filed July 13, 1916. Serial No. 108,979.

To all whom it may concern:

Be it known that I, CHARLES L. NEDOMA, a subject of the Emperor of Austria-Hungary, and residing at Detroit, in the county 5 of Wayne and State of Michigan, have invented a new and Improved Vehicle, of which the following is a specification.

The present invention relates to motor vehicles, and among its important features 10 are means whereby the driving force passing from the frame to the front axle is taken in tension rather than in compression; and transversely extending cantalivered springs whereby the weights of the sides of the 15 frame are transmitted, respectively, to the opposite end portions of the axle, thus allowing a much greater length of spring than can be obtained in the customary arched constructions.

20 The invention also consists in the details and arrangement of parts shown, described and claimed.

In the drawings, Figure 1 is a perspective view showing a preferred embodiment 25 of the invention. Fig. 2 is a horizontal section just below the upper flanges of the side bars showing the springs. Fig. 3 is an elevation of one end of the front spring and adjacent parts. Fig. 4 is a fragmentary 30 view showing more clearly the manner in which the rear spring may be mounted on the brake housing. Fig. 5 is a vertical section through the front cross-bar showing the manner of attaching the torque rods 35 thereto.

The side bars 1 of the frame are preferably of channel cross-section opening inwardly as shown and have their front ends 2 bent downwardly and joined by the cross 40 bar 3 (preferably tubular). The front axle 5, rear axle housing 6 (including the differential housing 7) and propeller shaft casing 8 are of a type well known, although these elements may be widely varied.

45 Surrounding the front cross bar at substantially its central portion is a two-part socketed element 10—11 (the parts being joined by bolts 12); and extending forwardly from the spring chairs 13, which are 50 secured to the front axle in any suitable way, are the converging torque rods 14 that terminate in a common forwardly extending portion provided with the spherical head 16 which is received in the socket. At their 55 rear ends the torque rods pass through the perforated bosses 17 on the spring chairs or brackets 18 and are secured by nuts 19.

The portion 11 of the socket element has a spherical outer face and is cut away at 20 to allow relative angular movements of the 60 frame and torque rods; the opening thus formed is closed by the stamped metal casting 20 which is thrust against the member 11 by a compression spring 26, the rear end of which bears on a collar 28 rigid with 65 the portion 15 of the torque rods. In use, the casing is filled with thick lubricant. Diagonal braces 29 may connect the element 10—11 to the front portions of the 70 side bars.

At a point above the front axle, the side bars are joined by a downwardly opening channel member comprising two substantially parallel end portions 30 and an intermediate portion 31 at an angle thereto; 75 the ends of the member 30—31 are joined to the respective side bars by angle brackets 32 and rivets or bolts 33 and 34 that pass, respectively, through the web and upper flange of the side bar. The end portions 30 80 of the channel member inclose the ends of springs 36 which are firmly held therein by shackles 38 or the like—these springs extend across beneath the opposite side bar and have their ends suspended on links 85 39 that are pivoted at 40 on the spring brackets 13. For the purpose of cushioning the lateral thrust, compression springs 42 are interposed between sockets 43 and 44 formed, respectively, on the spring chairs 90 95 and on the link members 39. The springs may be extended across the car on parallel lines, in which event the chairs 18 would be offset on opposite sides of the center line of the axle, or may be slightly curved, as shown, to bring them into proper relation to the aligned chairs.

Similar springs 36 and associated elements may be employed at the rear end of the car but in this case the chairs 13 are 100 preferably replaced by shackles or links 50 that are suspended on trunnions 51 (Fig. 4) carried by the rearwardly projecting ends of brackets 52 secured to or formed integrally with the brake housing 53 or 105 otherwise rigidly attached to the axle housing 6. In this manner the springs are supported far enough to the rear of the vertical plane through the axle to avoid danger of the springs 36 striking the differential 110 housing.

It will be observed that the springs are offset, both at front and rear, from the vertical planes through the axles.

The details of construction may obviously be changed within wide limits without departing from the spirit of the invention, and I do not, therefore, wish to be limited 5 otherwise than as indicated by the subjoined claims.

I claim:—

1. A motor vehicle comprising a frame, a front axle, said frame extending forwardly 10 past the front axle, resilient means extending longitudinally of the axle for supporting the frame on the axle, tension means connecting the frame and axle, said tension means being capable of angular movement 15 in respect to the frame, whereby stress on the frame, tending to drive it forwardly, is caused to pull the axle.
2. A motor vehicle comprising a frame, a front axle, said frame extending forwardly 20 past the front axle, resilient means extending longitudinally of the axle for supporting the frame on the axle, tension means connecting the frame and axle, said tension means being capable of universal angular 25 movement in respect to the frame, whereby stress on the frame, tending to drive it forwardly, is caused to pull the axle.
3. A motor vehicle comprising a pair of side bars, a front cross bar joining the side 30 bars, a front axle positioned to the rear of the cross bar, means extending longitudinally of the axle for resiliently supporting the side bars on the axle, and tension means for joining the outer portions of the axle to 35 the cross bar, said tension means being capable of angular movement with respect to the cross bar.
4. A motor vehicle comprising a pair of side bars, a front cross bar joining the side 40 bars, a front axle positioned to the rear of the cross bar, means extending longitudinally of the axle for resiliently supporting the side bars on the axle, and tension means attached to the cross bar near the center 45 thereof, said tension means also being attached to the axle near its outer ends and being capable of angular movement with respect to the cross bar, whereby stress on the side bars, tending to drive them forwardly, 50 is caused to pull the axle.
5. A motor vehicle comprising a pair of side bars, a front cross bar joining the side 55 bars, a front axle positioned to the rear of the cross bar, means extending longitudinally of the axle for resiliently supporting the side bars on the axle, a second cross bar joining the side bars at a point substantially over the front axle, and tension means attached to 60 the outer ends of the front axle and to the front cross bar whereby stress on the side bars, tending to drive them forwardly, is caused to pull the axle.

6. A motor vehicle comprising a pair of side bars, a front cross bar joining the side 65 bars, a front axle positioned to the rear of the cross-bar, a second cross-bar joining the side bars at a point substantially over the front axle, resilient means attached to said second cross-bar, said means extending longitudinally of the axle and being attached 70 thereto near its ends, and tension means, capable of angular movement in respect to the front cross-bar, joining the outer ends of the front axle to an intermediate portion of the front cross-bar whereby the thrust of 75 the resilient means longitudinally of the axle is reduced.

7. A motor vehicle comprising a pair of side bars, a front cross bar joining the side bars, a front axle positioned to the rear of 80 the cross-bar, a second cross-bar joining the side bars at a point substantially over the front axle, resilient means attached to said second cross-bar, said means extending longitudinally of the axle and being attached 85 thereto near its ends, and tension means, capable of angular movement in respect to the front cross-bar, joining the outer ends of the front axle to an intermediate portion of the front cross-bar whereby the thrust of 90 the resilient means longitudinally of the axle is reduced, and means for cushioning said longitudinal thrust of the resilient means.

8. A motor vehicle comprising a pair of 95 side bars, a front cross bar joining the side bars, a front axle positioned to the rear of the cross bar, means extending longitudinally of the axle for resiliently supporting the side bars on the axle, and tension means 100 for joining the outer portions of the axle to the cross bar, said tension means being capable of angular movement with respect to the cross bar and comprising a head, a socket in which the head is received, and a 105 casing for sealing the joint between the head and the socket, whereby lubricant may be retained.

9. A motor vehicle comprising a frame, a front axle positioned rearwardly from the 110 front end of the frame, spring means supported on the axle and extending longitudinally thereof for supporting the front end of the frame, and tension means for joining the forward portion of the frame to the 115 front axle, said tension means including a member whose horizontal projection extends at an angle to the axle whereby the thrust of the spring means longitudinally of the axle is reduced and whereby pulling force is applied from said frame to said axle, said member being capable of angular movement 120 in respect to the frame.

CHARLES L. NEDOMA.
